UNITED STATES PATENT OFFICE.

HERBERT M. SMITH, OF FARMINGTON, CONNECTICUT.

ELECTRICAL CONNECTION.

Application filed January 6, 1921. Serial No. 435,309.

To all whom it may concern:

Be it known that I, HERBERT M. SMITH, a citizen of the United States, residing at Farmington, county of Hartford, State of Connecticut, have invented a certain new and useful Improvement in Electrical Connections, of which the following is a full, clear, and exact description.

My invention relates to electrical connections, and has for its object to provide a hinged connection electrically connecting conductors carried by an operating handle with conductors carried by the member to which said handle is hinged without requiring the use of flexible conductors. It is particularly adapted for use with machines such as vacuum cleaners and floor scrubbing machines. Heretofore such connections have been made by means of flexible stranded conductors which, when subjected to use, are continually subjected to a bending or flexing action, so that the fine copper strands become crystallized and eventually break, rendering the device inoperative and requiring frequent repair. In my invention the connections are made by means of rubbing contacts so that the flexing or bending is eliminated, with the result that difficulties due to such flexing and bending are not present. A further object of my invention is to provide a simple and effective mechanical means in which the parts can be easily assembled and disassembled by unskilled persons.

The following is a description of my invention, reference being had to the accompanying drawings, in which,

Figure 1 shows a side elevation of a portion of a vacuum cleaner embodying my invention;

Fig. 2 is an enlarged side elevation of the lower end of the handle and the adjacent portion of the motor casing;

Fig. 3 is a section on the line 3-3 of Fig. 2;

Fig. 4 is a section on the line 4-4 of Fig. 5;

Fig. 5 is a rear elevation of the handle;

Fig. 6 is a section of the handle on the line 6-6 of Fig. 5;

Fig. 7 is a section on the line 7-7 of Fig. 3;

Fig. 8 is a detail of one of the bushings;

Fig. 9 is a side elevation showing in detail one of the contacts in its preferred form; and

Fig. 10 is a perspective view showing the relation of an eyelet contact and the insulation surrounding one of the pivot-pins.

Referring more particularly to the drawings, 1 is a motor driven device such for instance as a vacuum cleaner. 2 is the operating handle for the same having a central bore through which passes a pair of conducting wires 3. 4 are conductors connected to the motor of the machine. The handle is provided at its lower end with a metallic ferrule 5. This ferrule surrounds the lower end of the handle 2 and has at its lower portion a sleeve 6 having a transverse bore. Within the bore of this sleeve is an insulating tube 7 having slots 8-8 formed of each side of a separating portion 9. Located within the central portion of the tube 7 and in line with the portion 9 is an insulating disk 10. The tube and disk are held in place by a set-screw 10'. Upon each side of said insulating disk are metallic bushings 11-11. These bushings preferably have their inner ends closed as shown in Fig. 3. The sleeve 6, upon the lower end of the ferrule, is provided with an opening 12 which exposes portions of the bushings 11-11 lying beneath the slots 8-8. Mounted on these bushings and in line with said slots are binding screws 13-13 (Figs. 4 and 5), to which the ends of the conductors 3 are respectively connected, as shown in Fig. 5.

The frame of the motor driven device is provided with upward extensions 14-14 which have openings in line with the transverse opening in the sleeve 6. Fitting within these openings are pivot-pins comprising cylindrical insulating blocks 15-15, which carry reduced metallic portions 16-16, the same being provided with grooves 16' for lubricating material such as plumbago and projections 16'' which preferably make screw-threaded engagement with their insulating blocks respectively. These pins are also provided with circumferential metallic projections 17 forming shoulders at the bases of the reduced portions for the purpose hereinafter described. The insulation of the blocks 15-15 forming the enlarged portions of the pivot-pins is slightly counterbored so as to extend slightly beyond the outer faces of the shoulders 17 and form a recess for eyelet contacts 20. The free ends of the pivot-pins enter the bores within the bush-

ings 11—11 and make electrical contact therewith. They are also engaged by springs 18—18 which bear against the closed ends of the metallic bushings so as to form 5 electrical connections. The blocks 15 are held in place by suitable set-screws 19 so as to be easily removable. Between the opposing faces of the bushings 11—11 and the shoulders 17 are resilient contacts 20. These 10 contacts are preferably eyelets completely surrounding the reduced portions 16 and on account of their resiliency make constant lateral engagement with both the bushings and the pivot shoulders. Each 15 contact is provided with a downward projection 21, the lower end of which is surrounded with an insulating bushing 22 and forms means for connecting the contact to a conductor leading to or from the motor 20 so as to form a terminal therefor. The resiliency of the eyelets is produced by slitting them at the point 21 and bending the portions laterally, as shown in Fig. 9, the material being preferably of phosphor bronze. 25 The resiliency of the eyelets assists in maintaining electrical contact and compensates for wear of the contacting surfaces.

In connecting the handle to the machine, the bushings 11—11 are brought into alignment with the openings in the projections 14 and thereupon the pivot-pins comprising the insulating blocks 15 carrying the reduced portions 16 are slipped in place, the springs 18 having previously been introduced. The 30 blocks 15 are then secured by the set-screws 19. This brings the bushings 11—11 and the flanges 18 on opposite sides of the eyelet terminals so that the eyelet terminals and springs 18 are held under the desired pressure and form an electrical connection between the conductors 3 and the conductors 4 respectively, the current passing partly from one of the bushings 11—11 directly to the corresponding eyelet 20 and partly from 45 one of the bushings 11 through the spring 18 and pivot member 16 with its collar 17 to the corresponding eyelet terminal.

The shanks 21 of the eyelet terminal are held stationary relatively to the motor, this 50 being done by forming radial grooves at 15' in the inner ends of the blocks 15 in which those shanks are held, as shown in Fig. 10 and by the insulating bushings 22.

The upper portion of the sleeve 6 extends 55 over the end of the insulating block 15 and its lower side is cut away so as not to engage the shank 21 and make an electrical ground, whatever the position of the handle. The swinging motion of the handle is limited by 60 the motor housing 23 and the stop 24 on the fan casing.

With this construction the only exposed portions of the electrical circuit are those which appear through the opening 12 and 65 the portions of the shanks below the insulat-

ing blocks 15. The openings 12 can be filled with ordinary electrical sealing wax which insulates the conductors entirely at that point and also prevents the loosening of the binding screws 13. The other portions are so concealed as not to be accessible from a practical standpoint. 70

The construction thus described makes a durable and efficient hinged electrical connection in which there are no easily accessible exposed portions and in which the undesirable flexing and bending of conductors is entirely eliminated, so that a durable and efficient electrical connection is produced. Furthermore, the construction is such that it 80 can easily be assembled and disassembled and can be assembled by persons other than skilled mechanics. 85

As will be evident to those skilled in the art, my invention permits of various modifications without departing from the spirit thereof or the scope of the appended claims.

What I claim is:

1. The combination of a member having a transverse bore, a metallic bushing in said bore and insulated from said member, a second member having an opening in line with said bore, a removable pivot-pin secured therein having a metallic portion insulated from said second member and entering said bushing, and means for electrically connecting conductors to said bushing and said metallic portion. 90

2. The combination of a member having a transverse bore, a metallic bushing in said bore and insulated from said member, a second member having an opening in line with said bore, a removable pivot-pin secured therein having a metallic portion insulated from said second member and entering said bushing, means for electrically connecting conductors to said bushing and said metallic portion, and resilient means within said bushing forming an electrical connection between said metallic portion and said bushing. 105

3. The combination of a member having a transverse bore, a metallic bushing in said bore and insulated from said member, a second member having an opening in line with said bore, a removable pivot-pin secured therein and entering said bushing, and a resilient terminal contact bearing against the end of said bushing through which said pivot-pin enters, and a binding post on said bushing for connecting a conductor thereto. 115

4. The combination of a member having a transverse bore, a metallic bushing in said bore and insulated from said member, a second member having an opening in line with said bore, a removable pivot-pin secured therein and entering said bushing, a resilient eyelet contact forming a terminal surrounding said pivot-pin and bearing against the end of said bushing through which said 125 bushing 130

pivot-pin enters, and a binding post on said bushing for connecting a conductor thereto.

5. In an electrical connection, two relatively movable metallic members having portions provided with alining openings, a metallic bushing within the opening in one of said members and insulated from said member, a removably secured pivot-pin having an enlarged portion within the opening in 10 said other member and a reduced portion projecting into said bushing, a resilient contact embracing the reduced portion of said pivot-pin and bearing against the end of said bushing, and means for connecting conductors to said bushing and contact respectively.

6. In an electrical connection, two relatively movable metallic members having portions provided with alining openings, a 20 metallic bushing within the opening in one of said members and insulated from said member, a removably secured pivot-pin having an enlarged portion within the opening in said other member and a reduced metallic portion projecting into said bushing, a metallic shoulder connected to said reduced portion, a resilient contact embracing said reduced portion and bearing against the end of said bushing and said shoulder, and means 25 for connecting conductors to said bushing and contact respectively.

7. In an electrical connection, two relatively movable metallic members having portions provided with alining openings, a metallic bushing within the opening in one of said members and insulated therefrom, a removable shouldered pivot-pin having an enlarged portion within the opening in said other member and a reduced metallic portion 30 projecting into said bushing, a metallic shoulder connected to said reduced portion, a resilient contact embracing said reduced portion and bearing against the end of said bushing and said shoulder, means for connecting conductors to said bushing and contact respectively, said bushing being closed at its inner end, and a spring within said bushing engaging its inner end and the end of said metallic reduced portion.

50 8. In an electrical connection, two relatively movable metallic members having portions provided with alining openings, a metallic bushing within the opening in one of said members and insulated from said member, a removably secured pivot-pin having an enlarged portion within the opening in 55 said other member and a reduced portion projecting into said bushing, a resilient eyelet terminal embracing the reduced portion 60 of said pivot-pin and bearing against the

end of said bushing, means for connecting conductors to said bushing and contact respectively, and adjustable means engaging said enlarged portion and holding said pivot-pin in place.

9. In an electrical connection, two relatively movable metallic members, one of which has a single projection and the other of which has two projections embracing said single projection, said three projections having alining openings, two metallic bushings within the opening, in said single projection and insulated from its member, two removable pivot-pins each having a portion secured within one of the openings in said other member and a portion projecting into said metallic bushings respectively, two resilient contacts embracing the pins and bearing against the ends of said bushings, and means for connecting conductors to said bushings and said contacts respectively.

10. In a pivotal connection for an electrical apparatus, the combination of a member having a metallic projection on its lower end provided with a transverse bore, a tube of insulating material within said bore, two bushings within said tube, a second member provided with two metallic projections located at opposite ends of the bore in said metallic projection and provided with openings in line with said bore, pivot-pins removably secured in said openings and entering said bushing, the ends of said pivot-pins within said bushing being metallic and insulated from the second member, metal shoulders connected to said metallic ends and extending over the ends of said bushing, resilient contacts carried by said second member and engaging the opposing faces of said bushings and shoulders, and means for electrically connecting conductors to said bushings and contacts respectively.

11. The combination of two metallic members and a connection between said members constructed to permit pivotal movement of said members with relation to each other and to provide a pivotal electrical connection between and insulated from said members, said connection comprising two relatively fixed metallic elements in one of said members, and two relatively fixed metallic elements in the other member telescopically received within the first mentioned elements, respectively, and pivotally movable relatively thereto about a common axis, and means for connecting electrical conductors with said metallic elements.

HERBERT M. SMITH.
